CLAIM

The ornamental design for a combined chain container and step plate for tractors, substantially as shown and described.

DESCRIPTION

FIG. 1 is a perspective view of a combined chain container and step plate for tractors showing my new design;

FIG. 2 is a side elevational view thereof, wherein the opposite side is a mirror image of the side shown;

FIG. 3 is an end elevational view thereof, wherein the opposite end is substantially a mirror image of the end shown; and

FIG. 4 is a bottom plan view thereof.

FIG. 1

FIG. 2
